OPEN END RATCHET WRENCH

Weldon A. Wood, Nampa, Idaho

Application March 9, 1951, Serial No. 214,703

3 Claims. (Cl. 81—58.2)

1

This invention relates to wrenches of the crescent type used to turn tubing fittings, bolts, nuts, and the like, on continuous lines such as hydraulic and fuel supply tubing lines as used extensively on aircraft and other types of machinery, and in particular a crescent wrench having a rotatable socket member with the socket member actuated by ratchet elements to facilitate turning the tubing fitting, bolt, nut, or the like in a substantially inaccessible location.

The purposes of this invention is to provide an improved structure for wrenches of the crescent type whereby nut holding or gripping jaws positioned in the end of the wrench are actuated with the ratchet action.

Crescent wrenches are used universally and particularly where the size of the conventional monkey wrench prohibits its use, but wrenches of the crescent type have not been provided with ratchet elements because of the extremely narrow width required for wrenches of this type. With this thought in mind this invention contemplates a method of converting a wrench of the crescent type into a socket wrench without materially increasing the width thereof.

The object of this invention is, therefore, to provide means for mounting a rotatable nut receiving socket in the end of a wrench handle whereby the socket is actuated with a ratchet action and wherein the socket is readily removable from the handle.

Another object of the invention is to provide a ratchet wrench of the crescent type wherein gripping jaws are formed in a rotatable socket and in which the socket may be released from the wrench by a knob positioned at the outer end of the handle extended from the wrench.

A further object of the invention is to provide a crescent like ratchet wrench having a rotatable socket member therein which is of a simple and economical construction.

With these and other objects and advantages in view the invention embodies a wrench having a head with the handle extended therefrom, with a socket member having ratchet teeth in the peripheral surface rotatably mounted in the head by spring actuated holding members and in which the holding members are actuated by a stem extended through the handle of the wrench.

Other features and advantages of the invention will appear from the following description taken in connection with the drawing wherein:

Figure 1 is a side elevational view of the wrench.

Figure 2 is an elevational view looking toward one edge of the wrench.

2

Figure 3 is a longitudinal section through the wrench being taken on line 3—3 of Fig. 1.

Figure 4 is a similar view showing the socket gripping members or jaws extended outwardly and the socket removed.

Figure 5 is a longitudinal section through the wrench taken on line 5—5 of Fig. 2.

Figure 6 is a cross section through the wrench taken on line 6—6 of Fig. 5.

Figure 7 is a similar section taken on line 7—7 of Fig. 5.

Figure 8 is a side elevational view of the head of the wrench, with the socket shown in section, and with the socket holding jaws removed.

Figure 9 is a detail illustrating one of the socket holding jaws of the wrench.

Figure 10 is a detail showing the side elevational view of the socket of the wrench.

Figure 11 is a view showing a longitudinal section through the socket of the wrench.

Figure 12 is a view showing a cross section through the socket of the wrench.

Referring now to the drawings wherein like reference characters denote corresponding parts the improved ratchet type crescent wrench of this invention includes a head 10 having a handle 11, with a socket 12 rotatably mounted in an arcuate recess 13 in the head of the wrench, and the socket is secured in the recess by gripping jaws 14 and 15, resiliently held in engagement with the socket by a spring 16 and actuated to open positions as shown in Fig. 4 by a cam 17 on a stem 18 extended through the handle 11 and actuated by a knob 19.

The socket 12 which is of cylindrical shape is formed with rims 20 and 21 and the ratchet teeth 22 are positioned in an annular recess 23 which is located between the rims, as shown in Figure 12. The socket 12 is provided with a nut receiving opening 24 with the surfaces 25 and 26 of the socket positioned at the side of the opening, providing gripping jaws that are positioned to grip the flat surfaces of a nut, bolt head, pipe fitting, or the like.

With the socket 12 positioned in the recess 13 of the head of the wrench the rims 20 and 21 are positioned to receive arcuate extensions 27 and 28 on the inner surfaces of the jaws 14 and 15 with the jaws pivotally attached to the handle 11 by pins 29 and 30, as shown in Figure 5. The pin 29 extends through an ear 31 on the jaw 15 and through an ear 32 of the jaw 14 and the pin 30 extends through a similar ear 33 of the jaw 15 and an ear 34 of the jaw 14.

The extensions 27 and 28 of the holding jaws 14 and 15 extend under the rims 20 and 21 and,

thereby, provide means for rotatably mounting the socket member 12 in the arcuate recess 13 in the end of the head of the wrench. With the socket 12 held in this manner the spring pins 34 and 35 are positioned in openings 36 and 37, respectively, of the head 18. The springs which are resiliently held in position by springs 38 and 39, coat with the ratchet teeth 22 of the socket 12 whereby, as illustrated in Figure 5 the socket 12 is rotated in a clockwise direction as the handle 11 is actuated in a clockwise direction from the position shown in Figure 5. The pins 34 and 35 are provided with heads 40 and 41, respectively, by which the pins are retained in the openings 36 and 37.

The socket holding jaws 14 and 15 are provided with ears 42 and 43 in which the ends of the spring 16 are held as shown in Figs. 3 and 4. The spring 16 extends through an opening 44 that is positioned in the head of the wrench.

The inner surfaces of the jaws 14 and 15 are also provided with pins 45 and 46 that extend into an opening 47 in the head of the wrench and the inner ends of these pins engage the surface of the cam 17 which is positioned in the opening 47 and secured to the end of the stem 12 by a pin 48.

The cam 17 is rotated by the knob 19 and with the cam in the position shown in Fig. 3 gripping jaws 14 and 15 are nested against the opposite surfaces of the wrench head and extensions 27 and 28 are positioned in the rims 29 and 21 of the socket 12.

With the parts arranged in this manner and positioned as illustrated in Fig. 5 the nut held in the opening 24 of the socket 12 is turned in a clockwise direction by actuating the wrench and with the positions of the parts reversed so that the pins 34 and 35 slip over the ratchet teeth 22 when the handle 11 is turned in a clockwise direction, the nut, bolt, or pipe fitting may be unscrewed or rotated in a counterclockwise direction with the return movement of the handle.

The wrench may be provided in different sizes and the socket or opening 24 in the socket 12 may also be formed of different dimensions whereby a set, or a plurality of ratchets designed to receive nuts and the like of different sizes may be provided with one wrench.

It will be understood that modifications may be made in the design and arrangement of the parts without departing from the spirit of the invention.

What is claimed is:

1. A wrench having a head and a handle with an arcuate recess in the end of the head, a cylindrical socket member having ratchet teeth in the peripheral surface and having a nut receiving opening extended inwardly from one side, said socket member having annular rims on the opposite surfaces, gripping jaws pivotally mounted on the handle for movement outwardly of the plane of the handle and said jaws having arcuate extensions positioned to nest under the rims of the socket member for rotatably holding the socket member in the recess of the head, means resiliently holding the said gripping jaws within the plane of the handle with the extensions thereof nested under the rims of the socket member, means actuating said gripping jaws from the

end of the handle for releasing the said socket member, and spring actuated pins mounted in the head and positioned to coat with the ratchet teeth of the said socket member for rotating the socket member with the handles.

2. A wrench having a head and a handle with an arcuate recess in the end of the head, a cylindrical socket member having ratchet teeth in the peripheral surface and having a nut receiving opening extended inwardly from one side, said socket member having annular rims on the opposite surfaces, gripping jaws pivotally mounted on the handle for movement outwardly of the plane of the handle and said jaws having arcuate extensions positioned to nest under the rims of the socket member for rotatably holding the socket member in the recess of the head, means resiliently holding the said gripping jaws within the plane of the handle with the extensions thereof nested under the rims of the socket member, a stem having a knob on the outer end extended through the handle, and a cam mounted on the inner end of the stem and positioned to spread the said gripping jaws outwardly of the plane of the handle to release the socket member from the head, and spring actuated pins mounted in the head and positioned to coat with the ratchet teeth of the said socket members for rotating the socket members with the handles.

3. In a wrench of the crescent type, the combination which comprises a handle having a head on one end and said head having an arcuate recess in the end thereof, a cylindrical socket member having rims on the opposite edges with ratchet teeth positioned between the rims and with a nut receiving opening extended inwardly from one side positioned to extend into said arcuate recess in the end of the head, spring actuated pins positioned in opposite sides of the head and extended into the recess for engagement with ratchet teeth of the socket member, socket member holding jaws pivotally mounted on the wrench for movement outwardly of the plane of the wrench and said jaws having arcuate extensions positioned to extend into the rims of the socket member for rotatably retaining the said socket member in the recess of the head, a spring extended through the head and positioned with the ends connected to the said holding jaws for urging the jaws inwardly against the surfaces of the head within the plane of the head and with the said arcuate extensions nested in the rims of the socket member, a stem extended through the handle and having a knob on the outer end, a cam mounted on the inner end of the stem, and pins extended inwardly on the said holding jaws and positioned to engage the surface of the cam for moving the jaws outwardly of the plane of the head as the cam is rotated.
